UNITED STATES PATENT OFFICE.

ROBERT RADFORD, OF PHILADELPHIA, AND JAMES E. SHEAFFER, OF BURNHAM, PENNSYLVANIA.

MACHINE FOR CASTING WHEELS AND LIKE ARTICLE.

1,169,192.

Specification of Letters Patent. Patented Jan. 25, 1916.

Application filed March 2, 1912. Serial No. 681,122.

To all whom it may concern:

Be it known that we, ROBERT RADFORD and JAMES E. SHEAFFER, citizens of the United States, and residents of Philadelphia, county of Philadelphia, State of Pennsylvania, and Burnham, county of Mifflin, State of Pennsylvania, respectively, have invented certain Improvements in Machines for Casting Wheels and like Articles, of which the following is a specification.

The object of our invention is to provide mechanism for properly pouring two different metal compositions into the same mold.

The invention relates particularly to the molds which are rotated, and in which the molten metal is thrown against the inner periphery of the mold by centrifugal force; the invention being particularly adapted for molding or casting car or other wheels, or wheel blanks, in which the outer surface or periphery of the wheel, or blank, is of a metal harder than the body of the wheel.

In the accompanying drawing:—Figure 1, is a longitudinal sectional view of a rotary mold illustrating our invention; Fig. 2, is an end view; Fig. 3, is a sectional view of a wheel made in accordance with our invention; and Fig. 4, is a sectional view of the mold for forming wheel blanks.

A is the rotary mold made, in the present instance, of three parts C, C', and D, detachably secured together. The parts C, C' are the end plates of the mold and the part D is the intermediate ring or chill section of the mold. The several parts are shaped according to the design of wheel, or blank, to be cast. The section C is, in the present instance, an integral part of the shaft, which is adapted to bearings B, mounted on a foundation B'.

a is the pulley or gear by which the shaft is turned so as to rotate the mold at sufficient speed to cause the molten metal as it enters the mold to seek the inner periphery of the mold.

In order to properly pour the molten metal, it is essential that there shall be no time lost in the change from one metal composition to another, and, therefore, we have provided a pouring head I having two mouths i and i'. This pouring head is connected to the mold A by a coupling E which is secured to the pouring head. The coupling has a reduced

portion e in the present instance, adapted 55 to fit in a recess in the cap section C' of the mold. There is a throat opening from the pouring head I into the body of the mold. This throat opening is concentric with the shaft. The coupling is preferably lined 60 with a sleeve e' of fire brick or other material and the pouring head is also provided with a lining h of fire brick or other suitable material. The pouring head is made in two halves I', as shown in Fig. 2, and 65 these halves are connected together by bolts, or other fastenings, so that by this means in case of a stoppage the coupling head can be readily removed and parted and the obstruction withdrawn.

The pouring head is preferably mounted 70 on a carriage N having wheels n—n and may be attached to the coupling E in any manner desired. In the present instance, the pouring head has an extension which 75 enters a recess in the coupling head, and the coupling head is attached to the extension by means of screws f, so that it remains stationary while the mold is rotated.

The part D of the mold A is secured to 80 the part C by bolts c—c and the part C' is connected to the part D by detachable fastenings d so that after the casting is completed, the cap section C' can be detached and the molded wheel or blank re- 85 moved therefrom.

When it is desired to open the mold, the carriage N is backed away from the mold with the coupling E, after which the cap C' is attached to a crane and the fastenings d 90 removed, when the head can be swung out and the cast wheel or blank withdrawn.

In Fig. 3, we have shown a sectional view of a car wheel made in accordance with our invention in which the metal of the wheel 95 at the periphery x consists of a manganese or equivalent alloy and the body of the wheel is of soft steel. The compositions are intimately united during the process of casting to make a homogeneous steel structure. 100

In Fig. 4, we have shown a mold in which the end plates C² and C³ and the intermediate ring D have plain inner surfaces and are so proportioned as to make a mold for a wheel blank instead of a complete flanged 105 wheel. After this blank is cast it may be rolled in the ordinary process of making steel wheels. As the blank is a composite

casting with manganese at the periphery, this manganese will be at the tread of the finished wheel.

The operation is as follows: After the 5 mold and pouring head are in position, as illustrated in Fig. 1, the mold is set in motion so as to rotate at the proper speed. The ladle containing the manganese, or other alloy to produce the hard surface at 10 the periphery, being introduced in the present instance through the mouth *i*. The molten metal flows from this mouth through the channel in the pouring head and in the coupling *E* into the center of the mold and 15 will be immediately thrown out by centrifugal force against the inner wall of the section *D* of the mold, filling the mold to the required depth. The molten soft steel is immediately poured in through the mouth 20 *i'* before the entire mass of manganese alloy passes the lower end of said mouth so that the flow of the two metals is continuous and the softer metal is allowed to flow until the entire mold is filled and, as soon as the mold 25 sets sufficiently, the pouring head is withdrawn and the cap plate of the mold detached, after which the cast wheel or blank is removed from the mold and the resulting 30 product is a wheel or blank having a hard surface *x*, Fig. 3, at its periphery of any depth desired, with a comparatively soft steel center or body.

While we have illustrated a mold used in 35 the manufacture of car wheels, it will be understood that the invention may be used in casting wheels of other types, or any object requiring one character of metal on the periphery and another forming the body portion.

We claim:

1. The combination in a rotary machine for casting wheels and like articles, of a mold; means for rotating said mold, said mold having a central pouring opening; a single passage leading to the mold; a pouring head having two independent mouths; a passage leading from each mouth, one passage being below the other and communicating with the passage leading to the mold so that molten metal in one of said 45 passages may immediately follow the molten metal in the other passage.

2. The combination in a rotary machine for casting wheels and like articles, of a shaft; bearings for the shaft; a rotary mold carried by the shaft; means for rotating the mold; a pouring head having a passage therein leading to the mold and having two independent mouths; a passage leading from each mouth to the passage communicating with the mold, one passage being below the other; and a coupling secured to the head and having a passage therein communicating with the passage in the pouring head and with the center of the mold.

In testimony whereof, we have signed our names to this specification, in the presence of two subscribing witnesses.
